ALBERT G. STOOPS, OF INDIANAPOLIS, INDIANA.

WELL-SHOOTING-TORPEDO APPARATUS.

1,382,395.

Specification of Letters Patent. Patented June 21, 1921.

Application filed November 15, 1920. Serial No. 424,126.

To all whom it may concern:

Be it known that I, ALBERT G. STOOPS, a citizen of the United States, residing at Indianapolis, in the county of Marion and

5 State of Indiana, have invented a new and useful Well-Shooting-Torpedo Apparatus, of which the following is a specification, reference being had to the accompanying drawings and to the letters and figures of reference marked thereon.

This invention relates to the type of devices that are comprised in the class of torpedoes that are designed to be lowered into a well which may have been drilled to obtain oil, and when it is necessary or desirable to "shoot" the well as the operation of causing an explosion in the well is commonly termed, the invention having reference more particularly to a torpedo shell and an anchor 20 for the torpedo of the character above-mentioned.

An object of the invention is to provide an improved torpedo shell which shall be so constructed as to permit the torpedo to 25 be safely lowered into a well to be exploded.

Another object is to provide an improved torpedo shell which shall be of such construction as to permit it to be quickly and safely charged with an explosive, such as 30 nitro-glycerin, and to be handled without being liable to be accidentally exploded.

A further object is to provide a torpedo shell which may be constructed economically and at moderate cost, and which shall have 35 safety guides to guard against the torpedo being violently jolted in its descent into a well with a possibility of causing premature explosion.

A still further object is to provide an 40 improved and efficient yet not costly anchor for a well-shooting torpedo which shall be so-constructed as to be adapted to be used either as a plain anchor or as a loaded anchor in connection with a torpedo, and 45 which shall have guides thereon to guard the anchor when loaded to prevent premature explosion during its descent into a well.

With the above-mentioned and other objects in view, the invention consists in a 50 well-shooting torpedo apparatus comprising a novel shell and a novel anchor adapted to be used in connection with either the lower end or the upper end of the shell; and the invention consists also further in 55 the parts and combinations and arrange-

ments of parts as hereinafter particularly described and further defined in the accompanying claims.

Referring to the drawings, Figure 1 is an elevation of the improved torpedo shell 60 and the improved anchor connected with the lower end of the shell; Fig. 2 is an elevation of the improved shell and the anchor device connected with the top of the shell, as when used as a loaded anchor; Fig. 3 is a longitudinal central section of the torpedo shell as 65 preferably constructed and the anchor connected with the lower end of the shell; Fig. 4 is a longitudinal central section of the torpedo shell slightly modified and the anchor 70 arranged as a loaded anchor in connection with the top of the shell; Fig. 5 is a top plan of Fig. 1 slightly enlarged; and, Fig. 6 is the bottom end view of Fig. 1 slightly 75 enlarged.

Similar reference characters in the different figures of the drawings indicate corresponding elements or features of construction herein referred to in detail.

A practical embodiment of the invention 80 comprises a hollow cylindrical shell 1 which preferably is non-metallic, especially for the larger sizes of torpedoes, heavy straw-board or book cover board being suitable material of which to make the shell. A flat bottom 2 is arranged against one end of the shell, and it has a flange 3 embracing the outer side of the shell, and preferably a ferrule 4 is arranged against the inner side 85 of the shell and may be suitably secured to the bottom. A suitable non-metallic guard 5 is provided which is of plate form and arranged on the under side of the bottom 2, the guard preferably being composed of vulcanized fiber and being larger diametrically than the bottom extends outward beyond the bottom; and a metallic plate or disk 6 is arranged against the under side 90 of the guard. An annular top or ring 7 is arranged on the upper end of the shell 1, and has a flange 8 embracing the outer side of the shell, and preferably a ferrule 4' is arranged on the inner side of the shell and may be suitably secured to the top ring. A 95 non-metallic guard 9 of annular form is arranged upon the top 7. A funnel 10 is arranged in the guard and the top ring, and it has a supporting flange 11 thereon that is seated upon the annular guard. The 100 guard extends outward beyond the top ring 110

and the flange. A suitable number of tie rods 12, 13, 14 and 15 extend through the shell 1 and also through the plate 6. The tops of two of the tie rods have eyes 16 and 17 respectively that are adapted to operate as heads upon the flange 11 to secure the adjacent parts to the shell, and a bail 18 is connected with the eyes. Each of the remaining tie rods has a nut 19 on its upper portion engaging the flange 11, and a nut 19' on the lower portion thereof engaging the plate 6. Besides the opening in the smaller end of the funnel, the wall of the funnel preferably has apertures 20 therein 15 to permit rapid flow of nitro-glycerin through the funnel, the latter preferably having vent holes 21 in the upper portion of the wall thereof.

The lower end of the torpedo shell has a 20 tapered or conical end piece preferably in the form of a hollow tapered guide 22, having a flange 23 on its larger end which is seated against the plate 6 and suitably secured thereto, as by means of a screw ring 25 secured to the inner side of the guide and connected with a screw ring 25 secured to the plate 6. The smaller end of the guide has a collar 26 thereon beyond which extends a neck having screw-threads 27. An 30 anchor is provided for supporting the torpedo at a suitable distance above the bottom of the well and may be composed of any required number of sections, each section preferably being composed of sheet metal or tubing, tin plate or galvanized iron in some cases being suitable metal. One section 28 is provided which has screw-threads 29 to engage the screw-threads 27, and a flange 30 on the end of the section engaging a gasket 31 arranged against the collar 26. The section 40 has another collar 32 a short distance from its opposite end, and has also screw-threads 33 extending from the end. Another section 34 is provided which has 45 screw-threads 35 to engage the screw-threads 33, and also a flange 36 engaging a gasket 37 arranged against the flange 32. The section 34 has a tapered hollow guide 38 thereon to smoothly guide the section along the 50 wall of the well and prevent the section from being bent. The section has a collar 39 thereon below the guide and screw-threads 40 beyond the collar. Another section 41 is provided and has screw-threads 42 to engage the screw-threads 40, and has also a flange 43 to engage a gasket 44 arranged against the collar 39, the lower portion of the section having a collar 45 and screw-threads 46 55 beyond the collar. A lower section 47 is provided which has screw-threads 48 to engage the screw-threads 46, and has also a flange 49 to engage a gasket 50 arranged against the collar 45. The lower portion of the anchor has a bottom 51 therein which 60 preferably is secured in the lower portion

of the section 41. A hollow conical or tapering guide 52 is secured at its smaller end to the end portion of section 47 to guide the lower end of the anchor when descending in a well.

In some cases the torpedo may have a metallic shell 53 having flanges 54 and 55 on its ends, and a non-metallic guard 56 is arranged against the lower flange 54 and is adapted to perform the function of a packing ring against which a flat bottom 57 is arranged. The guard 56 is of suitable diameter so as to extend outward beyond the flange 54. Lug-bolts 58 have base plates 59 secured to the shell 53, the lug-bolts extending through the flange and the guard, and also through the flange 23 of the guide 22, and each lug-bolt has a nut 60 thereon engaging the flange 23. A non-metallic guard ring 61 is arranged on the flange 55, the funnel shaped top 10 is arranged in the upper portion of the shell with its flange 11 upon the guard ring, and lug-bolts 62 secured to the shell have nuts 63 securing the adjacent parts to the shell.

The guide 52 being tapered and adapted to be seated in the funnel 10 and the anchor adapted to be charged with an explosive such as nitro-glycerin, the anchor is provided with a funnel 64 to facilitate pouring of the explosive into the anchor, the funnel having a neck 65 on which is a collar 66 and also screw-threads 67 to engage the screw-threads 29 of a section that has the flange 30 whereby to force the gasket 31 to 95 the collar 66. The larger end portion or top of the funnel 64 is provided with ears 68 and 69 to which a bail 70 is connected.

In practical use after the shell is charged with a quantity of explosive, the plain anchor being connected to the guide 22, the torpedo and its anchor are lowered into a well, the guards on the torpedo preventing contact of metallic parts of the torpedo with the metallic casing in the well, thus 105 lessening danger of accidental explosion. After the torpedo has passed down beyond the well casing, the guides on the anchor and the guide 22 may encounter rough or jagged wall portions in the well but will not 110 catch and be obstructed thereon, the tapered guides smoothly sliding past the jagged rock wall portions and protecting the torpedo bottom from damage until the anchor is stopped on the bottom of the well. When 115 it is determined that the torpedo is in proper position, it is exploded by one of the well known devices, such as a jack-squib. In case it is desired to use a loaded anchor and explode it, the torpedo is lowered into the 120 well protected by the guide 22, after which the loaded anchor is lowered by means of its bail until the guide 52 becomes seated in the funnel 10. A jack-squib may be lowered into the funnel 64 and be caused to ex- 125 130

plode, resulting in explosion of the substance in the anchor followed by explosion of the torpedo.

Having thus described the invention, what is claimed as new is—

1. A well-shooting torpedo including a hollow cylindrical shell, a bottom and a non-metallic guard arranged together face to face opposite to one end of the shell, the guard extending outward beyond the bottom, clamping means to secure the bottom and the guard together to the shell, and a top part secured to the opposite end of the shell. 10
  2. A well-shooting torpedo apparatus including a hollow cylindrical shell, a bottom and a non-metallic guard having each a flat portion arranged together face to face against one end of the shell, means to secure the flat portions of the bottom and the guard together to the shell, a top part and a non-metallic guard having each a flat portion arranged together face to face against the opposite end of the shell, and means to 20 secure the flat portions of the top part and the guard together to the shell. 25
  3. A well-shooting torpedo apparatus including a hollow cylindrical shell, a top part and a guard having each a portion arranged opposite to one end of the shell and together secured to the shell, a bottom and a guide arranged together on the opposite end of the shell and secured to the shell, the guide being hollow and covering and protecting the bottom and having a screw-threaded neck thereon, and a hollow anchor detachably screwed to the neck of the guide and provided with a tapered guide extending about and secured to the anchor. 30
  4. A well-shooting torpedo apparatus including a hollow cylindrical shell, a funnel in one end of the shell and secured thereto, a guard connected to the funnel and the shell, a bottom and a hollow tapered guide arranged opposite to the opposite end of the shell, the guide covering and protecting the bottom and having a neck extending from the smaller portion thereof, a tubular anchor having a hollow 40
  - 50
  - 55
  - 60
  - 65
- of, a tubular anchor screw-threaded at one end correspondingly with the screw-threaded neck and having a hollow tapered guide encircling the anchor and fixedly secured at its smaller end to the anchor, a flat annular non-metallic guard arranged upon the upper end of the shell and extending outward beyond the shell, a funnel arranged in the shell and having a base flange seated upon the guard, the guard and the base flange being together firmly secured to the shell. 70
6. A well-shooting torpedo apparatus including a non-metallic hollow shell, a bottom and a non-metallic guard secured together to one end of the shell, the guard projecting beyond the outermost side portion of the shell, a separate hollow tapered guide firmly secured to the bottom and the guard, the guide covering and protecting the bottom, a funnel and a non-metallic guard secured together to the opposite end of the shell, the latter guard projecting beyond the outermost side portion of the shell, and a bail connected with the larger portion of the funnel. 80
7. In a well-shooting torpedo apparatus, the combination of a hollow non-metallic cylindrical shell, a bottom and a non-metallic guard arranged together on one end of the shell, the guard extending outward beyond the shell and the bottom, means connected with the bottom and the guard and the shell securing the bottom and the guard together and to the shell, an annular non-metallic guard seated on the upper end of the shell and extending inward and outward beyond the shell, a funnel arranged in the upper portion of the shell and having a base flange supported upon the annular guard, and means securing the base flange and the annular guard together and to the shell. 90
8. In a well-shooting torpedo apparatus, the combination of a plurality of tubular sections having screw-threaded end portions to be connected one to another, one of said sections having a bottom therein to support an explosive charge, a hollow tapered guide encircling one of said sections and having its smaller end secured to the section between its ends, a hollow tapered guide encircling another one of said sections and having its smaller end secured to the section adjacent to its end, a funnel having a neck screw-threaded and connected to one screw-threaded end portion of one of said sections and having also two ears on the larger portion thereof, and a bail connected to said ears. 100
9. In a well-shooting torpedo apparatus, the combination of a hollow cylindrical shell, a bottom on the lower end of the shell and having a flange embracing the outer side of the shell, a ferrule on the inner side of the shell and connected to the bottom, a non- 110
- 115
- 120

- metallic guard arranged under the bottom and extending outward beyond the bottom, a disk arranged under the guard and having a screw-ring fixed thereon, a top member 5 connected to the upper end of the shell, two tie-rods arranged within the shell and extending through the top member and also through the bottom and the disk, the tie-rods having eyes thereon respectively connected 10 with the top member, nuts on the tie-rods respectively in connection with the disk, a bail connected to said eyes, and a hollow tapered guide having a flange seated on said disk and having also a screw-ring engaging said first- 15 described screw-ring.
10. In a well-shooting torpedo apparatus, the combination of a hollow cylindrical shell, a bottom connected to the lower end of the shell, an annular top member seated 20 upon the upper end of the shell and having a flange embracing the outer side of the shell,
- a ferrule on the inner side of the shell and connected to the top member, an annular non-metallic guard seated upon the top member and extending outward beyond the shell, a funnel arranged in said member and in said guard and having a base flange seated upon said guard, the funnel having a vent-hole adjacent to its base flange, two tie-rods arranged within the shell and secured to said bottom, the tie-rods extending through the top member and the guard and also the base flange and having eyes respectively seated upon said flange, and a bail connected to said eyes. 35

In testimony whereof, I affix my signature in presence of two witnesses.
